Des. 239,479

Patented Apr. 13, 1976

239,479

SPORT SHOE

Jonas Senter, New York, N.Y., assignor to CITC
Industries Inc., New York, N.Y.

Filed Nov. 8, 1974, Ser. No. 522,248

Term of patent 14 years

Int. Cl. D2—04

U.S. Cl. D2—310

FIG. 1

FIG. 2

FIG. 3

FIG. 4

FIG. 6

FIG. 5

FIG. 1 is a right front perspective view of a sport shoe showing my new design;

FIG. 2 is a front elevational view thereof;

FIG. 3 is a left side elevational view thereof;

FIG. 4 is a top plan view thereof;

FIG. 5 is a rear elevational view thereof;

FIG. 6 is a partial left side elevational view of another embodiment of my new design of FIG. 1 wherein the uppermost, curved collar reinforcing tape has been replaced by extra stitching applied around the throat of the shoe.

The bottom of the shoe is plain and unornamented.

I claim:

The ornamental design for a sport shoe, as shown and described.
